WEATHER PROTECTOR

Joseph F. Fauner, Irvington, N. J.

Application June 17, 1933, Serial No. 676,397

1 Claim. (Cl. 20—66)

This invention relates to weather protectors for doors and windows, and its prime object is to provide a device of this kind which will automatically exclude the elements as rain, snow, 5 hail and wind, the moment the door or window is closed.

Another object of this invention is to provide in a device of this kind a stationary base structure, attachable to, or mounted with the existing frame 10 work of door or window openings, in which structure is provided a movable member, adapted to normally lay flat or flush with the stationary portion of the structure, and further adapted to rise or to be elevated above the structure, when the 15 door or window is being closed.

Still another object of this invention is to provide a suitable operating mechanism for said movable member, by means of which the latter is brought from its normal, flush position to its 20 elevated position, when actuated by the closing door or window.

A further object of this invention is to provide with the door or window an adjustable actuating element adapted to engage said operating mechanism at a predetermined position of the closing 25 door or window.

A still other object of this invention is to provide at the edge or edges of the door or window suitable means for forming a weather-tight connection between those edges and the elevated structure member, when the door or window is 30 fully closed.

The foregoing and still other objects will become more fully apparent from the following 35 description and the accompanying drawing, forming part of my disclosure, but not intended to limit me to the structures shown, and in which:

Figure 1 is an elevation, partially in cross-section, of the lower portion of a frame and a 40 door or window, equipped with my weather protector in its normal position, while the door or window is fully open.

Figure 2 is a partial top view of a corner of a frame and a door or window showing my device in the position illustrated in Figure 1.

Figure 3 is a cross-sectional view through my device in its operative position, with the frame and door or window indicated in broken lines.

Figure 4 is a partial top view of a door or window provided with my adjustable abutting element.

Figure 5 illustrates an elevation of a portion of a frame, and door or window in closed position.

Figures 6, 7 and 8 are profiles in elevation of modified forms of my structure and movable member, and

Figure 9 illustrates an elevation of another profile of my structure and a modified form of my weather-proofing attachment to the edge of a door or window.

Referring now to the drawing, numeral 10 denotes the weather side of a frame, while the inner frame portion is indicated at 11 and the middle portion at 12. Over the base line marked 13, is arranged my stationary structure consisting of the frontal portion 14, rear portion 15 and middle portion 16, in which latter is hinged at 17 movable member 18, shown in its normal, flat or flush position in Figure 1. Its swinging end is cut on a bias, as indicated at 19, which biased edge registers with the similarly cut face of inner member 16. Extending from movable member 18 endwise, is a pin 20, clearly seen in Figure 2, which pin is engaged by a slot 21, arranged in a flat lever 22. The latter is hinged at 23 and is provided at its inner end with abutments 24 and 25.

Numeral 26 denotes a door or window, which is hinged at c, indicating the center line of the hinge. Attached at the bottom edge and adjustably mounted, is an abutting element 27 adapted to engage abutment 24 of lever 22 when the door closes. This element extends from a flange 28, which is provided with longitudinal slots 29, which latter facilitate the positioning of the flange, so that the engagement between abutting element 27 and abutment 24 is so timed, as to cause the operation of lever 22, just before the complete closing of the door or window. (See Figure 5)

Abutment 25 of lever 22 is engaged by a plunger 30, which extends from a housing 31 and is propelled outwards by means of spring 32 lodged in the housing. (See Figure 2) Housing 31 is imbedded in the frame of the door or window, as clearly seen from Figures 1, 2 and 3. Through the action of piston 30 against abutment 25, lever 22 is constantly urged to assume the position shown in Figure 1 and only the closing of the door or window will cause a movement of the lever, in that abutting element 27 is caused to gradually engage and depress abutment 24, whereby the lever is caused to swing about its pivot 23.

When the door or window is brought to its closing position and is finally closed, lever 22 will assume the position shown in Figure 3, at which position movable member 18 will become elevated, while plunger 30 is depressed into the housing.

Door or window 26 is recessed, as indicated at 33, in which recess is mounted a resilient weather-proofing element 34, which latter is

adapted, when the door or window is being closed, to slip over the elevated, beveled edge of member 18, as clearly seen in Figure 3. This weather-proofing element forms a tight contact with the edge of member 18 and prevents rain, snow, 5
hail or wind from entering.

In Figures 1 and 3 it will be seen that between portions 14 and 16 of the stationary structure there is provided a drain-pipe, adapted to 10
carry water, deflected by member 18, when the latter is in its elevated position.

In Figures 1 and 3 are shown profiles of a preferred base construction, which, however, may be altered in shape and appearance, as clearly 15
seen in Figures 6, 7 and 8, all of which three latter figures are shown in just opposite position to that of Figures 1 and 3, in other words, the weather side of these three figures is at left. The stationary portion of Figure 6 is indicated at 20
35, while its elevatable member is marked 36. The arrow indicates the direction of operation of this member. In Figure 6 the stationary structure 37 has a left and right hand inclined approach, while the movable member 38 is very similar 25
25 to that shown in Figure 6. For certain limited thresholds, a construction shown in Figure 8 may be found preferable, in which a stationary member 39 is illustrated, provided with a hinged operating member 40.

30 A modified form of my device is illustrated in Figure 9. This modification is particularly intended to show a different construction of the weather-proofing element attached to the edge of the door or window. In this figure, numeral 35
41 denotes the stationary portion of my structure, upon which is hingedly mounted at 42 movable member 43, which terminates into a hook construction 44. The latter is adapted to interengage with a similar hook-shaped end 45 of 40
40 an angle 46, attached to door or window 47. When the movable element 43 is in its full line position, weather-proofing contact is established between the door and member 43. Movable member 43 is shown in its normal position in 45
45 broken lines.

50 All of the constructions illustrated are designed for draining moisture from within the stationary members, which are substantially channel-shaped, in cross section as in Figures 1, 6 and 7, or comprise other hollow forms such as shown in Fig. 9. The movable elements of all shapes are all intended for shedding water and for preventing its penetration to within the door or window.

55 Particular attention is directed to the connection between stationary and movable members, which forms a continuous hinge, the interlocking female and male parts of which are each made of one solid piece of material over the entire 60
60 length of the members, whereby an absolutely weather and water-tight connection is assured. Inasmuch as the structure extends far into the frame work of the doors or windows, there is no possibility of leakage anywhere.

65 Another important feature of my construction resides in the concealed, positive and unobstructive manner of attachment of the stationary member to the existing frames of doors and windows. The screw holes indicated in Figures 6, 7 70
70 and 8 are countersunk for the reception of wood screws or the like, which latter are intended to be entirely out of the way when the movable member is in inoperative position, i. e. when the device is exposed to the ordinary use for which it 75
75 is intended when the door or window is open.

Similarly notable is the fact that the construction of my device possesses no openings, crevices or places in which dirt, dust or other small obstructions may gather, which would be likely to interfere with the proper operation of the movable member, or prevent it from assuming its full closing position. The only possible place where small particles of dirt may lodge is between the end of the movable member and its positive and generous seat provided at the stationary members, as may be readily seen from Figures 6, 7 and 8. Inasmuch as such dirt may enter only when the device is in an inoperative position as shown, the possibility of foreign matter forming serious obstructions is very remote, 10
15 since the opening indicated between the two members, as illustrated in the figures, is exaggerated and actually does not exist in practice, the movable member being intended to abut tightly with the stationary member. 20

Moreover, the present construction is designed to do away with any auxiliary weather-proofing means, usually provided at the lower edge of doors, and frequently consisting of a solid bead extending along the entire threshold structure 25
25 and a hollow channel attached to the bottom of the door and adapted to cooperate with and to engage the bead. Such channel moves over rugs and mats when the door is operated, and gathers dust and fiber which becomes gradually 30 compressed into layers and eventually prevents the channel from fully engaging the bead. This results in the door not closing properly. The bead extending from the threshold structure in addition forms a dangerous obstruction over 35
35 which a person may easily trip. This is impossible with my device.

From the foregoing description it will be quite evident that my invention has decided advantages over present day methods of weather-proofing window-sills or thresholds, in that it eliminates completely all sorts of auxiliary devices for keeping tight the bottom or side portions of doors and windows, as for instance hooks, slip-bolts, snap-locks, etc., which latter 40
40 actually do not serve for any other purpose except for drawing close doors or windows to their frames, yet still do not prevent the entrance of elements into the cracks between the frames and the doors of windows. My construction also 45
45 shows that the stationary portion of my device can be attached without showing screws or other means of attachment when the door or window is open. My device also prevents damage usually caused by projecting auxiliary closing devices and eliminates jamming of the door or window or scraping by such devices. 50
55

The adjustable feature of my abutting element permits the elevation of the movable member at any degree of opening of the door or window. The drain-pipe provided in the device assures the conveying of water to the outside of the building, thereby preventing any accumulation of moisture behind the closed door or window. 60
65

It is to be noted that all of my weather-proofing devices are intended to extend over the entire length of a window-sill or door threshold, and that the movable member of the stationary base structure as well as the weather- 70
70 proofing element provided at the edge of the door or window and adapted to contact with the elevated movable member, also extends over the whole length of the base structure. Moreover my device may be secured to not only the win- 75
75

dow-sill or threshold, but may be applied to any other side, or all sides of a window or door.

While I have shown specific structures and forms of my device, it is quite evident that variations and improvements may be readily incorporated therein, and I therefore reserve for myself the right to make such improvements and changes as may become necessary when my invention is produced commercially.

10 I claim:

In a weather protector for doors or windows, adapted to either take the place of, or become permanently associated with a frame part of such door or window, a hollow, stationary, substantially channel-shaped base member having two approach edges, extending upwards and uninterruptedly over the entire length of the device, one of the edges forming a component part of a continuous hinge formation, a movable member operatively associated with said stationary member and provided at one of its edges with a continuous hinge formation corresponding to

and interlocked with the hinge formation of the stationary member, said hinge formations of both members adapted to form a dirt-proof, unobstructive and uninterrupted connection between the corresponding edges of the two members, while said movable member is either in its normal, downward, inoperative or closing position, or while it is in its swung-up, operative position, said hinge formation forming male and female shapes, having uniform cross-sections extending over the entire length of the device, the female portion encircling the male portion sufficiently to prevent disengagement of these portions, but permitting the required operation of the movable member, a plunger mechanism in cooperation with the door or window and said movable member for actuating the latter, and a recess in the door or window for accommodating and forming a weather-proof contact with said movable member, when the latter is elevated, while the door or window is closed.

JOSEPH F. FAUNER.
